UNITED STATES PATENT OFFICE.

RUDOLPH THIEM, OF HAMILTON, OHIO.

DESIGN FOR A STOVE OR RANGE.

SPECIFICATION forming part of Design No. 29,181, dated August 9, 1898.

Application filed July 16, 1898. Serial No. 686,156. Term of patent 7 years.

To all whom it may concern:

Be it known that I, RUDOLPH THIEM, a citizen of the United States, residing at Hamilton, Butler county, Ohio, have invented and 5 produced a new and original Design for a Stove or Range, of which the following is a specification, reference being had to the accompanying drawing, forming a part hereof and being a perspective view of a stove or 10 range embodying my new design.

The leading or material features of my design are shown in the drawing and may be described as follows, viz:

15 The leg-base 1 bears relief ornamentation consisting of double-ended foliate volutes 2 with their major convexities presenting downwardly, these two volutes flanking a similar but shallower volute, above which stand two similar volutes with their major convexities 20 in contact, the first-mentioned volutes 2 enclosing minor double-ended volutes with their major convexities upward, the corners of the leg-base being ornamented by double-ended foliate volutes.

25 The oven-door 3 bears relief ornamentation consisting of double-ended foliate volutes and foliate scrolls surrounding an irregular-shaped panel 4, having a pebbled ground margined by a series of double-ended volutes of 30 varying sizes.

The reservoir 5 bears relief ornamentation consisting of double-ended foliate volutes 6 and foliate scrolls.

The fire-door 7 bears relief ornamentation 35 consisting of double-ended foliate volutes 8 and foliate scrolls.

The ash-cup 9 bears relief ornamentation consisting of foliate scrolls.

The oven-shelf 10 has a wavy front margin 40 and its surface is ornamented by double-ended scrolls.

The front draft-door 11 is ornamented by an arched top panel having at its base a series of narrow arches over register-piercings.

45 The smoke-pipe section 12 has the form of

a pilaster substantially semicircular in cross-section and bearing relief ornamentation consisting of an elliptic foliate panel 13, surrounded by a foliate crown 15, the panel and crown being flanked by double-ended foliate volutes 14, the base of the section being ornamented by a series of register-piercings and double-ended foliate volutes.

The mantel-back 16 bears relief ornamentation consisting of interlaced work 17 and 55 double-ended foliate volutes 18, 19, and 20.

I claim as my invention—

1. In a design for a stove or range, the design for the leg-base, substantially as herein shown and described. 60

2. In a design for a stove or range, the design for the oven-door, substantially as herein shown and described.

3. In a design for a stove or range, the design for the reservoir, substantially as herein 65 shown and described.

4. In a design for a stove or range, the design for the fire-door, substantially as herein shown and described.

5. In a design for a stove or range, the design for the ash-cup, substantially as herein 70 shown and described.

6. In a design for a stove or range, the design for the oven-shelf, substantially as herein shown and described. 75

7. In a design for a stove or range, the design for the front draft-door, substantially as herein shown and described.

8. In a design for a stove or range, the design for the smoke-pipe section, substantially 80 as herein shown and described.

9. In a design for a stove or range, the design for the mantel-back, substantially as herein shown and described.

10. The design for a stove or range substantially as herein shown and described. 85

RUDOLPH THIEM.
